Primary Examiner — Dominic Simone(74) *Attorney, Agent, or Firm* — Marshall A. Lerner; Marvin H. Kleinberg; Kleinberg & Lerner, LLP(57) **CLAIM**

The ornamental design for shoe, as shown and described.

DESCRIPTION

FIG. 1 is a front perspective view of a shoe in accordance with my new design.

FIG. 2 is a rear perspective view thereof;

FIG. 3 is a right elevation view thereof; and,

FIG. 4 is a left elevation view thereof.

Broken lines showing the remainder of the shoe in the figures are for illustrative purposes only and form no part of the claimed invention.
